United States Patent Office

Des. 206,565
Patented Dec. 27, 1966

206,565

FOUNTAIN

Arthur Forney, 1670 S. Frederica Drive,
Clearwater, Fla. 33516

Filed Sept. 13, 1965, Ser. No. 86,957

Term of patent 14 years

(Cl. D91—4)

The figure is a side elevational view of a fountain showing my new design.

I claim:

The ornamental design for a fountain, as shown.
